UNITED STATES PATENT OFFICE

JOHN JANICKI, OF CHICAGO, ILLINOIS, ASSIGNOR TO WESTERN ELECTRIC COMPANY INCORPORATED, OF NEW YORK, N. Y., A CORPORATION OF NEW YORK

STRAND COVERING APPARATUS

Application filed July 7, 1930. Serial No. 466,082.

This invention relates to strand covering apparatus, and more particularly to a guide for effecting uniform and accurate lay of the insulating material on a core in strand 5 form.

The primary object of this invention is to provide apparatus for effecting uniform and accurate lay of strand covering material upon a core.

10 In accordance with this object, one embodiment of the invention comprises a hollow tube through which the conductor is advanced, one end of the tube being formed into two axial blades or forks of different lengths which 15 provide a narrow slot therebetween at one side of the conductor for receiving and winding the insulating material or threads about the conductor. One side of the blades are flat and offset slightly with respect to each other 20 for engaging and spreading the insulating threads before they pass into the slot and onto the conductor, and the blades are tapered on the opposite side to provide a V-shaped channel or surface which irons the helices of the 25 insulation on the conductor. A collar is secured around the middle of the tube for supporting an adjustable hook eye which directs the threads from the supply up into the slot between the blades and onto the conductor.

30 A clear understanding of the invention will be had from the following description of one specific embodiment thereof illustrated in the accompanying drawing, wherein,

Fig. 1 is an elevational side view of the 35 insulating guide, and a vertical sectional view of the insulating head to which the guide is attached;

Fig. 2 is a fragmentary plan view of this same apparatus;

40 Fig. 3 is a detail front view of the blades of the insulating guide taken on the line 3—3 of Fig. 2, and

Fig. 4 is a cross-sectional view of these 45 blades, taken on the line 4—4 of Fig. 3.

Referring now to the drawing in which like reference numerals designate similar parts in the several views, the insulation serving guide is disclosed therein as comprising a short vertical hollow tube 10 having 50 its upper portion slotted axially at 11 to

form two blades 12 and 13 which on their back sides are provided with flat surfaces 14 and 15 (Fig. 4), slightly offset with respect to each other, and on their front sides are tapered at 16 and 17 respectively, (Fig. 3) to 55 form a V-shaped channel or trough along which the electrical conductor is conveyed. Because of the fact that the blades 12 and 13 are tapered and form the V-shape channel it is to be noted that the blades will accommodate various diameters of conductor extending along said channel. A collar 18 split at 19 (Fig. 2) is clamped by a screw 20 around the lower end of the tube 10 and has two vertical lugs 24 and 25 forming an integral part 60 thereof which are provided with horizontal clamping slots 26 and 27 which may be closed or actuated by screws 28 and 29, respectively. A hook-eye 30 is threaded into the slot 27 and is secured therein by the screw 29 for guiding insulating material or threads from a supply and across the flat surface 14 at the back of blade 12 which spreads the material out flat, and then into the slot 11 between the blades. It will be understood that this 65 hook-eye 30 may be similarly secured in the lug 24 when the insulating threads are to be wound around the conductor in a clockwise direction, and that in the position shown the hook-eye is adapted for counter-clockwise 70 winding of the insulation. Flutings 31 and 32 in the front of the collar 18 are for providing sufficient clearance spaces for the threads to pass from the supply to the hook-eye according to whichever lug the hook-eye 75 is secured, without contacting the collar. The blade 12 is slightly longer than the blade 13 so that when the insulating material is tied to the conductor in starting the insulating operation the longer blade may be used in co-operation with the operator's finger to slide the thread down into the slot 11.

The above described insulation serving guide will operate in any ordinary insulating head in which the insulation is held under tension. In this case the guide is shown secured in a split collet chuck 36 formed in the upper end of the familiar rotatable hollow spindle 37 through which the electrical conductor 33 is advanced. A spool of insulat- 95 100

ing material 38, comprised of a plurality of silk strands in this particular case, is mounted on a metal sleeve 39 which may freely rotate upon ball bearings around an inner sleeve 40 splined to the spindle 37, these two sleeves being forced downwardly by a collar 41 threaded to the spindle and provided with plungers 42 which engage the inner sleeve to prevent rotation of the collar with respect to 10 said sleeve and the spindle. A flange 43 on the lower end of the freely rotatable sleeve 39 engages a fabric brake washer 44 mounted in a disc 45 which is resiliently supported by a spring 46 resting upon the bottom of a cup 15 50 which is fixed to the spindle and surrounds the spool 38. Due to the resilient supporting of the brake washer 44 against the flange 43 of the outer sleeve the tension in the threads or material 51, withdrawn from the 20 spool 38 and passed up through the eyelets 52 and 53 on the cup and to the serving guide, may obviously be regulated by screwing the collar 41 downwardly on the spindle. The unused eyelets 54 and 55 on the left side of 25 the cup 50 are provided for use when the material is wound clockwise.

In the operation of the thread serving guide the material 51 is first tied at its end to the conductor 33 and then slid down into 30 the slot 11 between the blades 12 and 13, at the same time placing the material 51 in the hook-eye 30 and adjusting the hook-eye in its threads in the lug 25 so that the hook-eye directs the material on an incline into the 35 slot 11 in a direction that the material will naturally take when it is being wound onto or around the advancing conductor. The spindle 37 with the cup 50 fixed thereto is at this time rotated counterclockwise as shown, 40 and the conductor 33 is advanced upwardly by means not shown. This rotation of the spindle 37, rotating with it the blades 12 and 13 whose tapered edges form the slot 11 through which the threads 51 extend, wraps 45 the threads 51 around the advancing conductor 33 in a spiral direction. The threads or material 51 is of course under regulated tension as aforementioned, the tension being provided by turning the threaded collar 41 50 around the spindle 37 and forcing the sleeves 39 and 40 downwardly until the sleeve 39 supporting the spool of thread 38 has its flange 43 engaging the brake washer 44 a sufficient amount. The tensioned threads 51 55 are directed by the hook-eye 30 over the flat surface 14 of the blade 12, and this flat surface spreads out the threads, silk they happen to be in this case, so that the threads assume a flat, ribbon-like form just before they engage and are wound onto the conductor by the blades 12 and 13.

Since the threads 51 are held under tension the threads pull the conductor 33 over into the channel trough-like groove formed by the tapered surfaces 16 and 17 of the blades

and against these surfaces, and thus these surfaces press against and iron down the helical turns of threads as these surfaces are rotated around the conductor to cause a finished uniform lay of the insulation around the conductor. In other words the tapered surfaces 16 and 17 operate as a wedge into which the conductor is pulled, and this wedging action causes these surfaces to iron and smooth out the threads around the conductor 75 as the surfaces rotate around it. Of course the slot 11 through which the threads enter is sufficiently narrow so that the conductor will not possibly be pulled through it. It is therefore apparent that the flat surface of one of the blades of the thread serving guide spreads out the insulating material or threads while the opposite tapered surfaces of the two blades iron the material around the conductor, and that the hook-eye 30 directs the threads over this flat surface and into the slot between the blades. 80

When the threads are to be served onto the conductor in the reverse direction to that shown the blades are rotated in the collar 18 a half turn and the hook-eye 30 is secured in the lug 24 so that when the threads are passed up through the eyelets 54 and 55 on the left hand side of the cup the thread will pass over the flat surface 15 of the blade 13 and onto the conductor in place of over the flat surface 14 of the blade 12. It is therefore believed to be apparent that this serving guide comprising the two vertical blades and the hook-eye secured to the central collar is simple in construction and efficiently serves the purpose of winding and ironing the insulating threads evenly and uniformly on the conductor. 95

Although the invention has been described in connection with one specific embodiment thereof, it will be understood, of course, that the invention is not to be limited thereto, but is to apply to the scope of the appended claims. 100

What is claimed is:

1. In an apparatus for serving material upon a core, a guide comprising a pair of parallel blades extending axially of the core for winding the material around the core and spaced apart a distance less than the diameter of the core, one of said blades extending beyond the outer end of the other blade to facilitate the threading of the serving material between the blades. 115

2. In a guide for serving insulating material upon an electrical conductor, a tube through which the conductor is advanced having a pair of parallel blades at one end extending axially of the conductor which provide a narrow axial slot therebetween through which the insulating material is fed for winding it about the conductor, said slot being open at the free end ends of the blades and one of the blades extending beyond the free end 125 130

of the other blade to facilitate the threading of the insulating material between the blades.

3. In a guide for serving insulating threads upon an electrical conductor, a tube through which the conductor is advanced having a pair of blades at one end forming a V-shaped channel extending along the conductor, the bottom of said channel being slotted longitudinally for receiving the insulating threads and wrapping them around the conductor, said slot being open at the free ends of the blades.

4. In an electrical conductor insulating thread serving guide, a rotatable tube through which the conductor is advanced having at one end a pair of parallel, wedge-shaped blades extending axially of the conductor and providing a narrow slot therebetween for receiving and winding the insulating thread around the conductor, a collar secured around the base of the blades, and a hook-eye threaded to the collar for directing the insulating thread into the slot.

5. In the insulating thread serving head of an electrical conductor insulating machine, a rotatable spindle through which the electrical conductor is advanced, a spool of insulating thread rotatably mounted around the upper portion of the spindle, means for resiliently resisting rotation of the spool to provide tension in the insulating thread as it is withdrawn from the spool, a tube secured to the upper end of the spindle and having a pair of narrowly spaced blades extending axially from its upper end to provide a slot for receiving the insulating thread withdrawn from the spool and winding it about the electrical conductor, one of the blades having its upper end extending above the upper end of the other blade to facilitate threading of the withdrawn thread into the slot, a split collar clamped around the middle of the tube at the base of the blades and having two symmetrically positioned lugs, each lug being provided with a threaded aperture, and a hook-eye threaded in one of said lug apertures for guiding the insulating thread from the spool into the slot provided by the blades.

In witness whereof, I hereunto subscribe my name this 27th day of June A. D., 1930.
JOHN JANICKI.
